United States Patent Office

Des. 195,131
Patented Apr. 30, 1963

195,131

STAR OR SIMILAR ARTICLE

Curtis Gunter, New York, N.Y., assignor to Austen Display, Inc., New York, N.Y., a corporation of New York

Filed July 23, 1962, Ser. No. 71,011

Term of patent 14 years

(Cl. D29—1)

FIG. 1 is an exploded view of a star or similar article, showing the outer part of my new design in collapsed-stacked position;

FIG. 2 is an exploded fragmentary side elevational view thereof;

FIG. 3 is an elevational view showing the design in an open position;

FIG. 4 is a sectional view taken on the line 4—4 of FIG. 3; and

FIG. 5 is a fragmentary sectional detail view taken on the line 5—5 of FIG. 4.

I claim:

The ornamental design for a star or similar article, substantially as shown and described.
